ARRANGEMENT FOR PRODUCING OPEN SPACES ON BUILDINGS

Filed July 15, 1930

UNITED STATES PATENT OFFICE

CARL AUGUST WINDEKNECHT, OF BERLIN, GERMANY

ARRANGEMENT FOR PRODUCING OPEN SPACES ON BUILDINGS

Application filed July 15, 1930, Serial No. 468,078, and in Germany July 27, 1929.

It is important for sport and exhibition halls, hospitals, kitchens, glass houses and other purposes to be able to quickly convert enclosed rooms into open rooms and contrarywise open rooms into closed rooms. This is effected, according to the invention in that the building is made either entirely or partly collapsible and the entire sections or their parts are movable by means of rolling 10 or sliding carrying elements.

Several embodiments of the invention are illustrated in the accompanying drawing in which:

Fig. 1 is a perspective of a building composed of individual telescopic building sections.

Fig. 2 is a plan view of the telescopic building, mounted on a single pair of rails.

Fig. 3 is a side elevation of the same.

Fig. 4 is a detail horizontal section on line C—D of Fig. 3 on a larger scale.

Fig. 5 is a detail rear elevation of the building shown in Fig. 4 and

Fig. 6 is a further form of construction.

My improved building comprises a number of sections slightly different in width and height and each one of the sections is made up of a roof and two side walls and all of the 30 sections are mounted so that they may slide in a right line and be telescoped one into another or partially withdrawn from one another.

In the form of construction shown in Fig. 35 1 the individual parts are telescoped in one another. In this instance three pairs of telescopic sections are provided and each section rests slideable or rollable on rails 7 so that the sections can be telescoped or extended.

In order that it is not necessary to have special rails for each telescopic section, on which the sections are rolled, it is also possible to allow all the sections to run on a single 45 pair of rails, as shown in the construction illustrated in Figs. 2 to 6.

Further the sliding surfaces of all the individual parts telescopic on rails may be so constructed that only the outer parts rest 50 on rails, whereas the inner parts are support-

ed on one another and on the outer parts, as shown in Figs. 2 to 6.

In the arrangement shown in Figs. 2 and 3 the centre building is divided into parts *a* and *b* of equal size and the following building sections *a*¹ and *a*² and *b*¹, *b*² respectively are each displaced by the thickness of a wall. The two centre building parts *a* and *b* respectively rest on rollers *c* on the rails *d*. A roller *e* is provided in the building section *a*, on which roller the building section *a*¹ is supported with the aid of a rail *f* (Fig. 5). On the other end of the building *a*¹ a roller *c*¹ is provided which runs on the rail *d*. Inside the building part *a*¹ a roller *e*¹ is arranged, on which the building section *a*² is supported by the rail *f*¹. The building section *a*² has a running roller *c*² at its opposite end. In this manner each building section runs on the rail *d* with one or more outer rollers *c*¹, *c*² and *c*¹', *c*²' respectively for the building side *b*¹, *b*² and is supported on the previous building section with the aid of inner rails and rollers. As the supporting rollers on the inner part of the wall are arranged 70 in grooves or the like, the walls can move quite close together and with this arrangement a loss of space is not necessary. The movements of the individual parts, one within the other, are limited by abutments or the like.

In the form of construction shown in Figs. 4 and 6, the rails *f*', *f*¹' rest inside the building walls *a*, *a*¹, whereas the rollers *c*', *c*¹' etc. are fastened on the following inner building 80 walls.

In an arrangement, according to the construction shown in Figs. 2 to 6, the removal of the telescoped building sections is effected from the separating line of the two centre parts *a* and *b* to both sides in opposite directions and can therefore be effected more quickly and the space previously enclosed and covered in is entirely opened.

Having now particularly described and ascertained the nature of my said invention and in what manner the same is to be performed, I declare that what I claim is:

1. A building, comprising in combination 100 telescopic outer building sections, a single

pair of rails carrying said outer building sections, and inner building sections supported by said outer sections.

2. A building, comprising in combination, 5 outer building sections, rails supporting said outer building sections, telescopic inner building sections, rails on said outer building section, rollers on said telescopic inner building section adapted to run on said rails 10 on said outer building sections, a rail, and rollers on the free end of said inner building sections adapted to support said inner sections and to run on said rail.

3. A building, comprising in combination 15 telescopic building sections, rails arranged in grooves in said building sections, and rollers on said building sections adapted to run on said rails.

4. A building, comprising in combination 20 telescopic sections, rails, on which said sections are telescopic, and bends on said rails adapted to prevent said sections from being pulled out too far.

5. A building, comprising in combination 25 telescopic outer building sections, rails supporting only said outer sections, and inner sections supported one on the other and on said outer sections.

In witness whereof I affix my signature.
30 CARL AUGUST WINDEKNECHT.
